Attorney

UNITED STATES PATENT OFFICE.

STEPHEN A. ELLETT, OF ELMIRA, NEW YORK.

STARTER FOR ENGINES.

1,400,040.

Specification of Letters Patent. Patented Dec. 13, 1921.

Application filed June 24, 1919. Serial No. 306,278.

To all whom it may concern:

Be it known that I, STEPHEN A. ELLETT, a citizen of the United States, residing at Elmira, in the county of Chemung and State of New York, have invented certain new and useful Improvements in Starters for Engines, of which the following is a specification.

My invention relates more particularly to 10 a starter for a gas engine and the like and the object thereof is to provide a simple, reliable and efficient automatic device of this character, consisting of a minimum number of parts which are easily accessible, assembled or taken apart and manufactured at a low cost.

Other and further objects of my invention will become apparent to those skilled in the art from the following description.

20 My invention consists of structural characteristics and relative arrangements of elements which will be hereinafter more fully described and particularly pointed out in the appended claims.

25 In the drawings, in which similar reference characters indicate the same parts in the several figures of the drawings,—

Figure 1, is a longitudinal vertical sectional view with parts in elevation, through 30 a structure embodying my invention in association with a dynamo-electric machine;

Fig. 2, is a fragmentary side elevation of the invention as shown in Fig. 1, partly in section;

35 Fig. 3, represents on a reduced scale detached and perspective views of several of the elements comprising the invention, and

Fig. 4 is an enlarged sectional view taken on line IV—IV of Fig. 1.

40 Referring to the drawings, 10 is a dynamo-electric machine provided with the usual poles 11, 11, armature 12 and commutator 13 carried by a hollow shaft 14 rotating in suitable ball bearings 15, 15 and is 45 capable of starting the engine when used as a motor, and generating electric current when used as a dynamo.

Longitudinally movable and non-rotatably supported within said hollow armature shaft 14 is a splined shaft 16, provided 50 at one end with a threaded portion 17 carrying and engaging an internally threaded pinion 18, the teeth 19 of which are adapted to mesh with teeth 20 on the periphery of a fly wheel 21 of a gas engine, not shown, for 55 purposes to be presently described. 22 is a

ball bearing on the outside of the motor casing and surrounding the splined shaft 16 and is reduced to form a shoulder at its outer section 23 to fit into a shallow depression or socket 24 in the inner end of the pinion 18 to form a firm support for said pinion 18 when in mesh with the fly wheel 20.

The other end of the splined shaft 16 is 60 threaded, as shown at 25, and provided with a shoulder 26 at the inner end of the threaded portion 25. Non-rotatably and firmly secured to the threaded end 25 and abutting against the shoulder 26 of the shaft 16 is a nut 27 having a series of keyways 28, 28, and a circular shoulder 29. 30 is a nut-lock 70 engaging the outer end of the threaded portion 25 of the shaft 16 and securely locking the nut 27 on said shaft 16 and against the shoulder 26. Surrounding the shaft 16 and interposed between and abutting against the inner side of the shoulder 29 and outer side of the washer 29' abutting against a shoulder on the outside of the hollow armature 80 shaft 14 is a coil or compression spring 31, which normally tends to move to the left the splined shaft 16 through the hollow shaft 14, for purposes to be presently described.

32 is a ratchet clutch member surrounding 85 the nut 27 and arranged between the nut-lock 30 and shoulder 29 and is provided with splines 33, 33, to engage the key-ways 28, 28, on nut 27, thereby permitting said clutch member 32 to have a slight movement on said nut 27 along the length of the shaft 16, with the nut lock 30 acting as a stop and locked against rotation round said shaft.

Arranged between the ratchet clutch 95 member 32 and shoulder 29 are a series of small coil springs 34, 34, preferably four as shown, which are held in position by pins 35, and are for the purpose of normally forcing the clutch member 32 toward and 100 against the nut-lock 30 and providing a longitudinally yielding connection between the nut 27 and member 32. Another ratchet clutch member 36 having ratchet teeth co-operating with the ratchet teeth on clutch 105 member 32 is secured by means of any suitable fastening means as a tapered pin 37 to a rotatable shaft 38 connected with the gears or other suitable means for conveying the rotary motion from the gas engaging 110 shaft, not shown, to the armature of the dynamo electric machine.

The parts being constructed and arranged as herein described, the operation of the device is as follows:

- The gas engine and dynamo electric machine being at rest, the parts are in the position shown in Fig. 1, and on energizing the electric motor 10, the armature 12, hollow shaft 14 and splined shaft 16 are rotated and causes the threaded pinion 18 on outer end 5 of shaft 16 to move from its outer position, as shown in Fig. 1, to its inner position, as indicated in Fig. 2, so that the teeth 19 of said pinion 18 mesh with the teeth 20 on fly wheel 21, this operation being effected 10 for the reason that the initial rotary torque exerted on pinion 18 by the splined shaft 16 is not sufficient to overcome the inertia of the pinion 18 and revolve it, consequently said pinion 18 moves longitudinally and inwardly into mesh with the fly wheel 21. After the pinion 18 abuts against the ball bearing 22 and its outer section or shoulder 23 is firmly seated in the depression or 15 socket 24 of the pinion 18, said pinion 18 applies power to and slowly rotates the fly wheel 21. After the pinion 18 is firmly seated against and rotatable on the ball bearing 22, and in mesh with the fly wheel 21, the continued and increased rotation of 20 the splined shaft 16 and the action of its threaded portion 17, with the corresponding internal threads of the pinion 18, causes the shaft 16 to move longitudinally within its hollow armature shaft 14 and carrying with 25 it the nut 27, nut lock 30, and clutch member 32 and completely compress the spring 31 between the shoulder 29 and washer 29', as shown in Fig. 2. In this position of the shaft 16 and relation of the nut 27 with the 30 compressing spring 31, and pinion 18 with respect to the fly wheel 21, the fly wheel 21 is rigidly geared by means of the pinion 18 to shaft 16, and the rotation of the armature 12, due to the energizing of the motor 10, 35 revolves the fly wheel 21 of the gas engine and cranks or starts the same. As soon as the gas engine has fully started and the motor 10 is deenergized or the shaft 16 and its pinion 18 are of such a rotary speed as to 40 permit the fly wheel 21 to have a speed greater than that with which the pinion 18 is able to keep up with, the pinion 18 is disengaged from the fly wheel and the shaft 16 and pinion 18 again assume the position 45 shown in Fig. 1, and the clutching member 32 is in driving engagement with the clutching member 36 by their interengaging ratchet teeth, and hence the rotation of the shaft 38, now having been set in motion by 50 the starting of the gas engine, is made to rapidly revolve the armature 12 and generate electricity for the storage batteries and ignition system.

From the foregoing disclosure of the construction and operation of my invention, it

will be seen that I have devised a starter which is simple and all the parts are easily manufactured, inspected and adjusted and requires no skilled mechanic to install the same or special machinery or castings to 70 make the several parts.

It is obvious that various other forms and modifications may be made and used without departing from the essential feature and principle of my invention and I do not wish 75 to be understood as limiting myself to the specific and preferred construction herein shown and described.

What I claim is:—

1. A starter for an engine comprising, in 80 combination with an engine driven member to start the same, a single dynamo electric machine having an armature, a shaft rotated by the engine carrying a clutch member, a combined movable and rotatable shaft 85 rotated by or rotating said armature and having a threaded section, a pinion movable on said rotatable shaft and engaging the threaded section of said movable shaft for engaging and actuating the engine driven member, and a clutch on said movable shaft for engaging and disengaging the clutch member on the shaft rotated by the engine. 90

2. A starter for an engine comprising, in combination with an engine driven member to start the same, a single dynamo electric machine having an armature, a shaft rotated by the engine carrying a clutch member, a combined movable and rotatable shaft rotated by or rotating said armature, a pinion loosely supported on one end of said movable shaft for engaging and actuating the engine driven member and also arranged and constructed to react against and move said movable shaft, and means on the other 100 end of said movable shaft for engaging or disengaging the clutch member on the shaft rotated by the engine. 105

3. A starter for an engine comprising, in combination with an engine driven member 110 to start the same, a single dynamo electric machine having an armature, a shaft rotated by the engine carrying a clutch member, a combined movable and rotatable shaft with- 115 in said armature and rotated by or rotating said armature, a spring normally reacting against the movement of said movable shaft, a combined movable and rotatable pinion loosely supported on one end of said movable shaft for actuating the engine driven 120 member and also constructed and arranged to react against and adapted to move the movable shaft, and means on the other end of said movable shaft for engaging or disengaging the clutch member on the shaft ro- 125 tated by the engine.

4. A starter for an engine comprising, in combination with an engine driven member to start the same, a single dynamo electric machine having an armature, a hollow shaft 130

within said armature and rotated by or rotating said armature, a shaft carrying a clutch member and rotated by the engine, a movable shaft supported within and rotated by said hollow shaft, a combined movable and rotatable pinion loosely supported on one end of said movable shaft for engaging and actuating the engine driven member and also constructed and arranged to react against and adapted to move the movable shaft, a spring normally reacting against the movement of said movable shaft within the hollow shaft, and means on the other end of said movable shaft for engaging or disengaging the clutch member on the shaft rotated by the engine.

10 5. A starter for an engine comprising, in combination with an engine driven member to start the same, a single dynamo electric

machine having an armature, a hollow shaft 20 within said armature and rotated by or rotating said armature, a shaft carrying a clutch member and rotated by the engine, a movable shaft supported within and rotated by said hollow shaft, a combined movable 25 and rotatable pinion loosely supported on one end of said movable shaft for engaging and actuating the engine driven member and also constructed and arranged to react against and adapted to move the movable 30 shaft, a spring normally reacting against the movement of said movable shaft within the hollow shaft, and a clutch nut on the other end of said movable shaft for engaging or disengaging the clutch member on the shaft 35 rotated by the engine.

In testimony whereof I affix my signature.

STEPHEN A. ELLETT.
